1 **1 Claim. (Cl. 48—197)**

This invention relates to gaseous fuel mixtures and more particularly to such fuel mixtures that have a high calorific value and a low ignition point.

Fuel mixtures of this type are in demand for use in metallurgical and other industrial operations in which an intense local heat is required, as for instance, in cutting metals, hardening and annealing, scarfing, melting and welding metals and the working of lead, hard glass and silica. For these purposes, the oxy-acetylene and oxy-hydrogen flames have been widely used but both are comparatively expensive, and in the case of acetylene, because of high carbon content and critical nature of the flame, unless great precautions in use are observed, it is liable to be dangerous and costly and work may be spoiled.

It is an object of the present invention to provide a cheap gas mixture by raising the calorific value and lowering the ignition point of the ordinary fuel gas, such as coal gas and natural (petroleum) gas supplied for general public use which will be referred to hereinafter as "city gas."

The gas mixture may be made in the first instance and compressed in cylinders and used direct from the cylinders to the burner. Alternatively, the supplementary gaseous material required to raise the calorific value and lower the ignition point of the city gas may be obtained from material compressed in cylinders and supplied from the cylinder to the city's gas in pipe lines by means of suitable flow meters.

Various proposals with the above object in view have been made hitherto. There are, however, difficulties involved in making a gas mixture as above described from, for example, ordinary city gas by making additions to raise the calorific value and lower the ignition point and produce a gas which is comparable for the purposes above described with acetylene. Suitable materials for addition are necessarily of an easily condensable character, such as the higher hydrocarbons and gas mixtures supplied in the usual city mains consist mainly of the more permanent gases, of which hydrogen, carbon monoxide and methane are examples. When substances are added with a view to increase the calorific value and lower the ignition point, in many cases such substances condense under pressure in the cylinders, and when the cylinder is opened to supply a burner, direct or through pipe lines, imperfect diffusion of the constituent gases may occur and a homogeneous gas, such as acetylene will not be supplied to the burner. Moreover, when the rapidly

moving stream of gas meets the oxygen supply there may be also imperfect diffusion with consequent deleterious effects upon the intensity of the flame and its resulting temperature.

5 It has now been found possible by proper selection of the added material and the proportions in which it is used to produce a gas mixture which, whether used from a cylinder or formed in the pipe line by introducing compressed material from a cylinder, will give a homogeneous mixture at the point at which ignition occurs and which may be used with oxygen in the same way as acetylene and produce comparable results.

10 According to the present invention a gaseous fuel mixture consists in city gas and petroleum ether, the proportion of the latter being 5-10 lbs. for every 1,000 cubic feet at 70° F. and at atmospheric pressure of the city gas. The petroleum

ether referred to is the petroleum fraction having

15 boiling point ranges from approximately 40° C. to 60° C. at atmospheric pressure, such, for example, as benzin.

Other petroleum ethers with higher boiling

20 points may be used in the proportions stated provided means are employed to vaporize the material sufficiently for proper diffusion with the city's gas before ignition occurs.

The petroleum ether lowers the ignition point

25 of the gas and raises the calorific value, retards

flame propagation and greatly intensifies the

flame thereby imparting a greater flame tem-

perature than is possible with city gas alone.

These properties enable the gas mixture to be

30 used in like manner to acetylene for the pur-

poses hereinbefore enumerated and is particularly

effective for use in aluminum welding, burning of

lead and like purposes for which pure hydrogen

35 has hitherto been used. The gaseous fuel may

be distributed through a pipe line under the nec-

40 essary pressure, depending primarily upon the

work for which it is required.

Although the minimum proportions above-

45 mentioned are effective for the purposes stated,

the maximum proportions are desirable for all

uses on thick or rusty metals, for blowing holes

46 or bevel cutting and the like. The proportions

will also be chosen within the specified range

according to the calorific value of the city gas

supplied.

Although a certain specific embodiment of the

invention has been shown and described, it is

obvious that many modifications thereof are pos-

sible. The invention, therefore, is not to be re-

stricted except insofar as is necessitated by the

55

prior art and by the spirit of the appended claim.

That which is claimed, as new, is:

A gaseous fuel mixture having a high calorific value and a low ignition point, which mixture consists of city gas as herein defined and petroleum ether, said petroleum ether being a petroleum fraction boiling over the range of 40° C. to 60° C. at atmospheric pressure, said mixture being in the proportion of 5-10 lbs. of the petroleum ether for every 1000 cubic feet at 70° F. 10 of the city gas.
